Richard G. Galef, New York, N. Y., assignor to The Ravenware Company, Inc., Brooklyn, N. Y., a corporation of New York

Application June 30, 1954, Serial No. 31,236

Term of patent 7 years

(Cl. D85—2)

FIG. 1

To all whom it may concern:

Be it known that I, Richard G. Galef, a citizen of the United States of America, residing at New York city, in the county of New York and State of New York, have invented a new, original, and ornamental Design for a Figure Ash Tray or Similar Article, of which the following is a specification, reference being had to the accompanying drawing, forming part thereof.

In the drawing

Fig. 1 is a rear perspective view of a figure ash tray or similar article, showing my new design; and

Fig. 2 is a front perspective view thereof, to an enlarged scale.

I claim:

The ornamental design for a figure ash tray or similar article, substantially as shown.
